UNITED STATES PATENT OFFICE.

CHARLES A. FOSTER, OF PORTLAND, OREGON.

CULVERT.

997,383.

Specification of Letters Patent. Patented July 11, 1911.

Application filed December 19, 1910. Serial No. 598,259.

To all whom it may concern:

Be it known that I, CHARLES A. FOSTER, a citizen of the United States, residing at Portland, in the county of Multnomah and 5 State of Oregon, have invented a new and useful Culvert, of which the following is a specification.

My invention relates to culvert constructions and has for its object the provision of 10 an abutment adapted to be secured to the intake end of a culvert to prevent the dirt around the mouth of the culvert from being washed away by the action of the water which flows through the culvert.

15 Referring to the accompanying drawings, Figure 1 is a perspective view showing a culvert section and the two sections of my new form of abutment, which are adapted to fit snugly around the culvert section, the parts 20 being in this figure shown disassembled, Fig. 2 shows the parts of Fig. 1 assembled in operative relation, Fig. 3 is a view showing a different form of culvert section and a correspondingly modified abutment plate to be 25 secured thereto, the figure showing the parts disassembled, and Fig. 4 is a view showing the parts of Fig. 3 assembled in operative relation.

In its preferred form my novel form of 30 abutment comprises a pair of complementary plates 1 and 2 constructed of corrugated sheet metal. These plates are recessed at 3 and 4, respectively, the precise configuration of the recesses depending on the shape of the 35 culvert to which the abutment is attached. In Figs. 1 and 2, the abutment is shown in connection with a culvert section 5 of substantially cylindrical form. In this case the recesses 3 and 4 are semi-circular so that 40 when the plates 1 and 2 are brought together the opening formed by the recesses 3 and 4 is substantially circular. When the culvert is constructed of corrugated sheet metal, as it preferably will be, the size of the opening 45 formed by the recesses 3 and 4 is such that the abutment plates snugly fit into one of the corrugations of the culvert. This is shown in the assembly view of Fig. 2. The plates 1 and 2 are provided with lateral 50 flanges 6 and 7. When the plates are assembled these lateral flanges 6 and 7 abut against each other, as shown in Figs. 2 and 4. Suitable fastening devices 8, such as bolts or rivets, pass through the flanges 6 and 7 and 55 firmly hold the abutment plates together on the culvert.

In Figs. 3 and 4 the abutment is shown in connection with a culvert having a flat bottom 9 and an arched upper piece 10. In this case the recesses 3 and 4 of the abutment 60 are of such configuration that when the abutment plates are secured in place on the culvert the plates snugly embrace the culvert section.

It will be seen from the above description 65 that the lateral abutting flanges afford simple and effective means for securely holding the plates in position on the culvert. Although I have herein shown the abutment as constructed of two complementary plates, 70 it is obvious that the number of such plates may be varied. For instance, in case of abutments of large dimensions, it may be that more than two plates would be required to build up the abutment economically. 75 However, for ordinary culverts, a pair of complementary plates will be sufficient to make up the abutment.

Having thus described my invention what 80 I claim as new and desire to secure by Letters Patent of the United States is:

1. The combination with a culvert, of an 85 abutment therefor, said abutment comprising a plurality of complementary plates constructed to fit around the body of the culvert, the contiguous edges of said plates being provided with lateral flanges which extend at right angles to the body of the plates and are adapted to abut against each other when the plates are brought together into 90 operative position, and securing means engaging said flanges for holding the plates rigidly together on the culvert.

2. The combination with a corrugated 95 metal culvert, of an abutment therefor, said abutment comprising a plurality of complementary plates constructed to fit snugly into one of the corrugations of the culvert, the contiguous edges of said plates being provided with lateral flanges which extend at right angles to the body of the plates and are adapted to abut against each other when the plates are brought together into operative position, and securing means engaging 100 said flanges to hold the plate rigidly together on the culvert.

3. The combination with a corrugated 105 metal culvert, of an abutment therefor, said abutment comprising a plurality of complementary plates constructed of corrugated metal to fit snugly into one of the corrugations of the culvert, the contiguous edges of

said plates being provided with lateral flanges which extend at right angles to the body of the plates and are adapted to abut against each other when the plates are brought together into operative position, and securing means engaging said flanges to hold the plates rigidly together on the culvert.

4. The combination with a culvert, of an abutment therefor, said abutment comprising a plurality of complementary plates of corrugated metal constructed to fit around the body of the culvert, the contiguous edges of said plates being provided with lateral flanges which extend at right angles to the body of the plates and are adapted to abut against each other when the plates are brought together into operative position, and securing means engaging said flanges to hold the plates rigidly together on the culvert.

20 5. The combination with a culvert, of an abutment therefor, said abutment comprising a plurality of complementary plates constructed of corrugated metal to fit around the body of the culvert, lateral abutting flanges provided on the contiguous edges of said plates and running transversely to the corrugations, and securing means engaging said flanges to hold the plates rigidly together on the culvert.

30 6. The combination with a corrugated culvert, of an abutment therefor, said abutment comprising a plurality of complementary plates constructed of sheet metal to fit snugly into one of the corrugations of the culvert, lateral abutting flanges provided on the con-

tiguous edges of said plates and running transversely to the corrugations on the plates, and securing means engaging said flanges to hold the plates rigidly together on the culvert.

40

7. The combination with a culvert, of an abutment therefor, said abutment comprising a plurality of complementary plates constructed to fit around the body of the culvert, the contiguous edges of said plates being provided with lateral flanges which extend at right angles to the body of the plates and are adapted to abut against each other when the plates are brought together into operative position, and bolts passing through said flanges for holding the plates rigidly together on the culvert.

45

50

8. The combination with a culvert, of an abutment therefor, said abutment comprising a plurality of complementary plates of corrugated metal constructed to fit around the body of the culvert, the contiguous edges of said plates being provided with lateral flanges which extend at right angles to the body of the plates and are adapted to abut against each other when the plates are brought together into operative position, and bolts passing through said flanges to hold the plates rigidly together on the culvert.

60

In witness whereof, I hereunto subscribe my name this 9 day of Dec. A. D. 1910.

CHARLES A. FOSTER.
